Primary Examiner — T Chase Nelson(74) Attorney, Agent, or Firm — Banner & Witcoff, Ltd.CLAIM

The ornamental design for a shoe, as shown and described.

DESCRIPTION

FIG. 1 is a bottom view of a shoe showing my new design; FIG. 2 is a front perspective view thereof; and, FIG. 3 is a rear perspective view thereof.

The contrast in shading between the three regions in the forefoot and in the rearfoot represents a contrast in color appearance. The broken lines depicting the remainder of the shoe represent features that form no part of the claimed design.
